DESIGN FOR A JEWELRY FINDING FOR CLIPS OR OTHER SIMILAR ARTICLES OF JEWELRY

Madge E. Lytell, New York, N. Y., assignor to Tabby, Ltd., New York, N. Y.

Application January 8, 1941, Serial No. 97,881

Term of patent 3½ years

To all whom it may concern:

Be it known that I, Madge E. Lytell, a citizen of the United States, residing at 143 E. 39th Street, in the county of New York and State of New York, have invented a certain new, original, and ornamental Design for a Jewelry Finding for Clips or Other Similar Articles of Jewelry, of which the following is a specification, reference being had to the accompanying drawing, forming part thereof.

In the drawing:

Fig. 1 is a front elevational view of a jewelry finding for clips or other similar articles of jewelry showing my new design; and

Fig. 2 is an edge view thereof.

I claim:

The ornamental design for a jewelry finding for clips or other similar articles of jewelry, as shown.

MADGE E. LYTELL.
